United States Patent Office

Des. 198,076
Patented Apr. 28, 1964

198,076

STEP

Nunzio Sgroi, 972 Monument, Pacific Palisades, Calif.

Filed June 10, 1963, Ser. No. 75,289

Term of patent 3½ years

(Cl. D13—7)

FIG. 1

FIG. 2

FIG. 3

FIG. 4

FIGURE 2 is a top plan view thereof in which the lower portion represents the front of the step and the upper portion represents the rear of the step;

I claim:

The ornamental design for a step, substantially as shown.
